UNITED STATES PATENT OFFICE.

PERCY H. PINDER, OF NEW YORK, N. Y., ASSIGNOR TO THE STANDARD STEAM SPECIALTY COMPANY, A CORPORATION OF NEW YORK.

STEAM-SEPARATOR.

1,239,823.

Specification of Letters Patent. Patented Sept. 11, 1917.

Application filed February 9, 1917. Serial No. 147,580.

To all whom it may concern:

Be it known that I, PERCY H. PINDER, a citizen of the United States, residing at New York city, in the county of New York and State of New York, have invented a new and useful Improvement in Steam-Separators, of which the following is a specification.

This invention relates to a combined steam separator and feed water heater, and has special reference to improvements upon the apparatus shown in the patent to Roberts No. 720,740, dated Feb. 17, 1903.

The object of the present invention is to provide a more efficient separation of the grease, oil or other matter suspended in exhaust steam, and at the same time to prevent short circuiting of the steam around the separating baffles. The steam sometimes tends to pass over the surface of the oil drip compartment and below the separating baffles, without being cleaned. This is found to be due to the greater resistance of the steam path through the baffles, as compared with the less resistant path through the drip chamber below the baffles. By the present invention, this difficulty is avoided, at the same time a partial purification of the steam is effected, and the drips separated, before the main purification of the steam in passing through the chain baffles.

The invention is shown in a preferred form in the accompanying drawings wherein,

Figure 1 is a longitudinal section of a separator and feed water heater embodying the invention,

Fig. 2 is a cross section.

1 represents the body of the separator of generally cylindrical form having the inlet 2 for exhaust steam, or steam which is to be purified, and opening into the preliminary muffling, separating, and expansion chamber 3. The heavy materials carried in the steam tend to separate from the steam as it enters chamber 3, owing to its expansion, reduction in velocity and change of direction, and heavy drips are drawn off through outlet 4. Chamber 3 is provided with a dam plate 5 and separated therefrom is a second dam plate 6 having its upper portion inclined, as shown, and closing the entire body, so as to separate the secondary drip chamber 7 and the discharge chamber 8 from the feed water reservoir 18. 9 rep-

resents rows of chain baffles which are carried by separable frames 10 supported in position on angle irons 11 running lengthwise between the dam plates 5 and 6. Intervening between the groups of chain baffles, are frames 12 which are also provided with chains and carrying the baffle plates 13 by means of angle irons 14 extending nearly to the bottom of chamber 7. These baffle plates 13 in the secondary drip chamber 7 prevent the steam from flowing around below the chain baffles, and also have the function of adding additional separating surface without causing the total capacity to be reduced. After the steam has passed through the chain baffles into chamber 8, any further condensation runs down the inclined surface of the dam plate 6 into the chamber 7, and steam which passes out through outlet 15 is completely cleaned, and able to be further used in any desired manner. As herein shown the clean steam may be discharged from outlet 15 into a heating system and thence into the feed water reservoir 18 by return inlet 21, or may be discharged directly into chamber 16 and thence by pipe 17 into the feed water reservoir 18. 19 is a cold water supply tube which discharges through a water nozzle 20, and 26 is a pipe which receives the returns from inlet 21. The clean steam entering chamber 16 heats both the returns which are discharged in the form of a lateral spray from nozzle 22 carried by pipe 26, and also the cold make up water which is similarly discharged by nozzle 20 connected to tube 19 inside pipe 26, the heated water flowing by gravity through pipe 17 into the feed water reservoir 18. The water in reservoir 18 can overflow after a certain level is reached, or can be controlled by a float in a well understood manner, being drawn off as required through pipe 23.

The heavy drips from chamber 7 can be withdrawn through plug 25 and chamber 18 may have a plug 24 for blow-off purposes.

The various accessories which may be used, such as a governor controlled feed pump, etc., are not shown herein, as devices for controlling the water level of a feed water heater of this type and for supplying and taking water therefrom are well known and do not require further description.

What is claimed, is:

1. A steam separator comprising an ex-

2
pansion chamber having drip retaining means, a dam plate at the inner lower end thereof, a baffle chamber above and horizontally beyond said dam plate containing 5 large surfaced flexible baffles, a dam plate closing said baffle chamber, a single secondary drip chamber below said baffle chamber and between said dam plates opening freely into said baffle chamber, and means 10 in said secondary drip chamber obstructing the steam flow therethrough to a greater extent than the normal flow through said baffles.

2. A steam separator comprising an expansion chamber effecting an initial separation and having its bottom closed to retain drip, a baffle chamber containing oil separating flexible baffles communicating with the upper portion of said expansion chamber, a secondary drip chamber below said baffles, separated from said expansion chamber at the bottom by a partition and opening freely in said baffle chamber, vertical baffles in said secondary drip chamber for 20 obstructing the steam flow therein to a greater extent than through said first mentioned baffles, a plate closing both the first baffle chamber and the secondary drip chamber 25

ber and a steam outlet from said baffle chamber. 30

3. A steam separator comprising an expansion chamber effecting an initial separation by expansion and change of direction of steam flow and having its bottom closed to retain drips, a baffle chamber communicating with the upper portion of said expansion chamber containing a series of flexible baffles, and separated at the bottom from said expansion chamber by a partition, a secondary drip chamber formed by said 35 partition below said baffle chamber, plate baffles spaced above the bottom of said secondary drip chamber below said first named baffles for obstructing the steam flow in said secondary chamber to a greater extent 40 than through said flexible baffles, a second partition having its upper end inclined upwardly away from said baffles and closing both the baffle chamber and the secondary drip chamber, and a steam outlet from said 45 baffle chamber above said inclined portion. 50

In testimony whereof, I have signed my name to this specification, this 8th day of February 1917.

PERCY H. PINDER.
